(57) **CLAIM**

The ornamental design for a display screen with animated graphical user interface, as shown and described.

DESCRIPTION

FIG. 1 is a front view of a display screen with animated graphical user interface showing the first image in a sequence.

FIG. 2 is a front view thereof showing the second image in the sequence.

FIG. 3 is a front view thereof showing the third image in the sequence.

FIG. 4 is a front view thereof showing the fourth image in the sequence.

FIG. 5 is a front view thereof showing the fifth image in the sequence; and,

FIG. 6 is a front view thereof showing the sixth image in the sequence.

The appearance of the animated graphical user interface sequentially transitions between the images shown in FIGS. 1-6. The process or period in which one image transitions to another image forms no part of the claimed design.

The broken-line rectangular border illustrates the edges of a display screen and forms no part of the claimed design. The remaining broken lines illustrate portions of the graphical user interface and form no part of the claimed design.
